PROCESS OF CONTROLLING AND PLACING OF RADIO-FREQUENCY HEAT IN A DI- ELECTRIC

Julius W. Mann and George F. Russell,
Tacoma, Wash.

Application May 27, 1947, Serial No. 750,836

5 Claims. (Cl. 219—47)

1

This case is a continuation-in-part application of the case filed by us on November 26, 1943, for a Process of Controlling the Placing of the Heat in the Interior of Material by a Radio Frequency Standing Wave, Serial No. 511,882 now abandoned.

In our patent on a single Standing Wave Radio Circuit, No. 2,506,158, issued May 2, 1950, we disclosed how it is possible to set up a single standing wave in a radio circuit and make the load or work an inherent part of the inductance and capacity, thus eliminating the necessity of matching impedance and resonance as between a master oscillator and a separate resonant output circuit. We further showed that substantially the entire length of the half-standing wave was in the inductance portion in the fundamental circuit and substantially the entire length of the other one-half standing wave was in the capacitance portion of the circuit. It was pointed out in the pending case that the inductance portion of the fundamental circuit had two points of greatest energy loss and it was at these two points that the taps of the grid circuit were connected. This caused the oscillator tubes in the circuit to be biased properly with a minimum of effort and equipment.

There are two additional power wave crests in the capacitance portion of the circuit and the present invention deals mainly with this feature of the circuit and sets forth how the power wave crests can be altered to heat dielectrics in different manners. For example, if the opposite walls of a tube are to be heated to a greater extent than the remaining portions of the tube wall, the radio circuit and associate apparatus may be adjusted to heat the two portions of the tube wall to a greater degree than the rest of the tube.

Again it might be desirable to heat the dielectric more uniformly and to accomplish this the two spots of greatest heat energy are developed in the dielectric at points spaced a sufficient distance apart so that the conduction of heat through the dielectric and between the spots will raise the temperature of this portion of the dielectric substantially to that of the temperature of the hot spots themselves. Also it is desirable sometimes to heat the dielectric to a higher temperature than that created by the two individual power crests and this is accomplished by bringing the current and voltage more into phase with each other and merging the two power crests into what appears as one and thus obtaining the result of the increased center peaked temperature.

2

Other objects and advantages will appear in the following specification, and the novel features of the device will be particularly pointed out in the appended claims.

5 Our invention is illustrated in the accompanying drawing forming a part of this application, in which:

Figure 1 is a wiring diagram of the single standing wave radio circuit shown in our Patent No. 2,506,158; No. 510,566, filed November 16, 1943.

Figures 2 and 3 show graphs of current and voltage curves;

Figure 4 illustrates a power curve when current and voltage are 90° out of phase;

15 Figure 5 illustrates a different power curve when the current and voltage curves are partially in phase;

Figure 6 by graph and illustration indicates heating in the capacitance or inductance and shows the merging or the separating of the two hot spots; and

20 Figures 7, 8 and 9 illustrate three different types of heating on three different types of dielectric.

25 While we have shown only the preferred forms of our invention, it should be understood that various changes or modifications may be made within the scope of the appended claims without departing from the spirit and scope of the invention.

30 In carrying out our invention we make use of the single standing wave radio circuit illustrated and claimed in our Patent No. 506,158. In our patent, the fundamental circuit comprises the inductance L, see Figure 1, and the capacitance 35 W. The plate tank or restorative force circuit is inductively coupled to the fundamental circuit by the center of the inductance L' of the restorative force circuit being inductively coupled to the current anti-nodal point of the inductance

40 L of the fundamental circuit. The grids of the tubes T and T' have their taps 1 and 2 adjustably connected to the inductance L at points of great energy reaction. The results obtained from the proper adjustment of these points with reference 45 to the energy reaction are indicated at 4a 4a in Fig. 6 and will be referred to more particularly hereinafter. An energy consuming dielectric placed in the capacitance W will bring the voltage and current into phase and change the position of the crests of the power curves. The grid taps 1 and 2 will be connected to the inductance L at energy crest positions which means the grids will receive proper excitation and bias in connection with the grid bias resistance. Because

50 but a single standing wave resides in the circuit, grid and plate swings will increase simultaneously

and absorb a greater restorative force, which in turn allows a greater power consumption in the dielectric.

In Figures 2 and 3 we graphically illustrate the current and voltage curves of a single standing wave in the capacitance W and inductance L of the circuit shown in Figure 1. The plates P and P' of the capacitance W of Figure 1 are shown spaced along the X-axis which indicates time in both Figures 2 and 3 with the capacitance being indicated by W and the inductance by L in these figures so as to agree with the showing in Figure 1. The current curve I is illustrated as leaving the plate P (the plate P is shown twice in Figures 2 to 6, inclusive, in order to graphically illustrate the endless circuit) and simultaneously flowing through both the capacitance W and the inductance L to the plate P' and then returning to the plate P, note the arrows in Figure 2.

The voltage curve is 90° out of phase with the current curve when there is theoretically no resistance in the circuit. The voltage curve is indicated at E in Figure 3 and is at maximum when the current curve is zero. The voltage is zero in both the capacitance W and inductance L of Figure 1 when the current is maximum and vice versa. The arrows on the curve E portion lying in the capacitance W in Figure 3 indicate the changing of the voltage from maximum at the plate P to zero midway between the plates P and P' and back to maximum at the plate P', and also indicate the return or other half cycle in the same voltage line E. Simultaneously the voltage in the inductance L starts at maximum at the plate P, drops to zero at the current antinodal position and again rises to maximum at the plate P'. The second half cycle is also indicated by the return arrow to the plate P in the inductance portion of the circuit L and on the same line E in Figure 3. In both Figures 2 and 3 the arrows above the X-axis time line show direction in one half the cycle while the arrows below the X-axis show directional effects during the second half of the cycle.

The power distribution curve Y shown in Figure 4, illustrates what happens when the current curve I and the voltage E are 90° out of phase. There are two power crests in the capacitance portion W of the circuit and two power crests in the inductance portion L. This is the condition of wattless power where all of the energy put into the circuit during the first quarter cycle is returned to the generator in the second quarter of the cycle, and likewise all of the energy put into the circuit during the third quarter is returned to the generator in the fourth quarter cycle. Only the first and second quarters are here shown. In actual practice the current and voltage curves are never 90° out of phase. Figure 4 illustrates a theoretical condition when there is no resistance in the circuit. Figure 5 illustrates the change in the standing wave distribution curves Y when current and voltage are brought more into phase by the placing of an energy consuming dielectric in the capacitance W or by placing a conductor in the inductance L. The small loops Y' are the negative power loops. It will be seen that much more power is consumed in the circuit during the first quarter than is returned to the generator in the second quarter of the cycle and also more is consumed in the circuit during the third quarter than is returned to the generator in the fourth quarter of the cycle. The whole cycle

is depicted here, rather than only a half cycle as in Figure 4 described above.

In Figure 6 the power distribution curves Y lying below the X-axis shown in Figure 5 are swung through an arc of 180° and are indicated by the dotted lines. The resultant heat placement in the capacitance W and in the inductance L are indicated by the heat curves H. The two curves will be similar in the inductance and the capacitance portions and their overlapping will be in a similar proportion. The heated areas, therefore, in the dielectric portion W will be similarly disposed along the X-axis to those in the inductance portion L. The inductance portion L may be variable as may be the capacitance portion W, but in any event the entire composition of L and W being a resonant circuit will have matched impedance in the condition of proper operating efficiency. Under such a circumstance, therefore, the heat placement will be similarly disposed in each section. Below the time X-axis line in Figure 6 in the capacitance portion W is a representation of the dielectric 3 disposed in such section with the area 3a of greatest heating effect centered as if a single burn. Under the X-axis in the inductance portion L is a representation of the inductance 4 showing the two spot heat effect at 4a respectively merged into a single peaked effect which, in an inductance, is equivalent to the apparent single burn in the dielectric disposed in the capacitance portion W.

The spots of greatest heat in the dielectric or conductor may be altered in their positions with respect to each other by: one, controlling the length of the inductance and the size of the electrodes or plates P and P'; two, altering the total mass and shape of the dielectric and its dielectric constant; three, altering the phase angle between the current and voltage which in turn is governed by changing conditions one or two, and; four, employing cauls of thicknesses and dielectric constant. The heating effect on the dielectric is controlled by the phase angle shift and the shift is controlled by the varying of the inductance and capacity and the relative resistance of the load.

We show three examples of different types of heating dielectric for various commercial purposes in Figures 7, 8 and 9. Figure 7 illustrates a thermo plastic tube A to be heated on its two sides in order to be bent. Internal pressure is built up within the tube by an air inflated bag or hose, not shown, and the tube is placed between a pair of cauls 5-5. The cauls are used as spacers between the plates P and P' and the tube A and prevent physical contact of the plates with the tube. Condenser plates P and P' are disposed at the sides of the cauls and are connected to the radio frequency inductance L. The centers of the power distribution curves Y coincide with the heat curves H which in turn have their peaks falling at the two points 6-6 at opposite sides of the tube. The portions of the tube lying between these two points will not be heated to the same extent and therefore the plastic tube wall will be softened at the two points and the tube when removed can be bent with the greatest heated portions forming the top and bottom portions of the tube during the bending process.

Where a more uniform heating is desired such as the bonding of material forming a resin bonding grinding wheel B in Figure 8, the cauls 7-7 are placed between the sides of the wheel and the plates P, P' so that the crests of the power dis-

tribution curves Y will fall adjacent to the sides of the wheel. The power peaks can be made to overlap each other to a greater extent than in Figure 7. The overlapping portions of the power curves will create a combined heat to cause the central peak of the heat curve H to be substantially as great as the hot spots formed by the power crests. The result is a substantially uniform heating across the entire width of the wheel. Note that the uniform heating does not extend from plate to plate of the condenser.

Peak heating results where the power distribution curves are brought still more into an overlapping relation. A thermosetting plastic preform D is illustrated as the load in Figure 9 and this may be placed between cauls which in turn space the preform from the electrodes or condenser plates P, P', or no cauls may be used, either method securing satisfactory results. The overlapping power curves are indicated at Y and their overlapping portions create the peaked heating shown at H in the same figure. The high peaked effect indicates that the two hot spots are merged sufficiently to heat the interior of the preform to a greater extent than the individual heat created by each spot.

By actual experiment with the above three examples of Figures 7, 8 and 9, we found that a two spot separation of heat was accomplished by increasing the spacing between the plates, thereby lessening the capacitance and by physically lengthening the inductance to increase it, as in Figure 7. The dielectric mass A in this figure created less capacitance than the dielectric masses B and D in Figures 8 and 9, respectively. In obtaining the two spot overlap for the single center burn as in Figure 9, the capacity was made larger and the inductance relatively smaller than the same components in Figure 7. The more even distribution of Figure 8 was accomplished by a compromise of the capacitance and inductance from the more extreme cases shown in Figures 7 and 9.

The two burned areas shown at 4a in Figure 6 and at 6 in Figure 7 is a result of a shift in phase of the current and voltage which is less than that which causes a center burn. The burned spots are close together at 3a in Figure 6 and also in Figure 9, when the phase shift is greater and the in phase relationship between the electrical components is closer than where the burned spots are separated. When the phase angle between the current and voltage approaches 90°, there is very little energy absorption and the two burned areas are substantially one-fourth and three-fourths the distance between the two plates. As the phase angle approaches zero and maximum energy absorption is effective, the two heated areas merge to form a single area of a higher temperature. Then the heating effect becomes the practical equivalent of $E I$ or current squared.

It should be noted that the placing of a dielectric in the capacitance or a conductor in the inductance does not alter the fact that but one single standing wave resides in the fundamental circuit. The circuit can be so adjusted by the variable condenser C in Figure 1, that the placing of an energy absorbing dielectric in the capacitance W will so change the frequency of the circuit that without further adjustment maximum power output will become effective. The circuit can also be adjusted by the variable condenser C so that by placing a conductor in the combined inductances portion will so change the frequency of the circuit that without further ad-

justment maximum power output will be effective. Either loading the capacitance as in dielectric heating and eliminating other variable or loading the inductance as in induction heating have the same net effect, and either method is the key to continuous process operation of electronic heat treating.

The loading of the capacitance as in dielectric heating does not necessitate the material contacting the electrodes; making possible heating very high dielectric constant materials without shorting the circuit.

Following is a description of the method used for recording the heat pattern produced by the standing wave pattern of the electric field of force existing between the condenser plates P and P' of a high frequency dielectric heater:

A one-eighth inch thick sheet of asbestos proved to be a material which had the qualities best suited for the purpose in hand for the following reasons, namely:

1. Asbestos withstands a high temperature.
2. It may be dried down to a bone dry condition readily.
3. It is very absorbent to moisture.
4. It is highly resistant to any rapid heat transfer.
5. Its white color is advantageous to contrast.
6. It loads the R. F. generator to a stable condition.

The chemical used on the asbestos was cobaltous nitrate which decomposes at a lower temperature than the boiling point of water; and upon high temperature, yields nitrogen tetroxide, oxygen and cobalt oxide, the latter being a brown solid. Hence, wherever the electric field releases energy at the greatest rate there will appear a brown area on the white asbestos.

The procedure.—Due to the release of free oxygen, when the cobaltous nitrate decomposes, we find that paper, wood or any combustible substance will start burning fiercely in the field even though the substance is very wet or damp. Hence, the use of asbestos paper. Apply the cobaltous nitrate solution to one side of the asbestos sheet by means of an atomizer or ordinary garden spray hand pump. The areas which absorb heat at the greatest rate of course rise rapidly to higher and higher temperatures and these areas first appear as pinkish blue due to the crystallization of the cobaltous nitrate as the sprayed-on coating becomes dry. Soon, in a matter of seconds, the salt decomposes releasing oxygen and the brown fumes of nitrogen tetroxide. As a consequence, red hot areas may even result on the asbestos surface, registering temperatures greater than 600° F. while a fraction of an inch away the temperature may be well below the boiling point of water. As the field is kept on, these heated spots spread, leaving the brown oxide of cobalt deposited upon the surface of the asbestos paper as a permanent record of the non-uniform generation of heat created by means of a half wave of electric field between the plates P, P' of the condenser.

The term "charge" used in the subsequent attempt to explain the phenomena observed, refers to a quantity of electricity, i. e., electrons. A charge is associated with an electric field, the latter's intensity changing with the change in the charge. Current flows at any point in a conductor because there is an electric field as the initiator of the current. Due to a changing electric field occupying an evacuated space between the plates P, P' of a condenser, a chang-

ing magnetic field is set up just as if a real electron disturbance existed between the spaced electrodes. Such a fictitious current is known as a "displacement current."

If any material substance is placed between the above electrodes P , P' , then the changing electric field will initiate a displacement of electrons whether the electrons are free or bound. From measurements taken of standing waves on helical lines (a coil) as compared to the standing waves set up by the same frequency on a similar conductor of approximately the same length, but stretched out straight, it is found that, in a sense, the speed of propagation may appear less in traversing the length of the axis of the helix as compared to traversing the length of the straight conductor. If the helix is terminated by condenser plates P and P' and it is admitted that a half standing wave exists across the coil terminals, then it is reasonable to expect a half standing wave of electric field to exist across the gap between the condenser plates, thus completing a full standing wave system.

Traveling waves are said to obtain when maximum values of charge and of axial current occur simultaneously at the same cross-section of the conductor; a condition of zero reflection. Standing waves are said to obtain when nodes and antinodes form at fixed points along the conductor, these nodal points being due to the nullification and reinforcement of the reflected wave meeting the incident wave. In this case, the maxima of current density occur at instants differing in time by a quarter period and at locations differing in position by the equivalent of a quarter wave length from those of the maximum density of charge. Stated another way, standing wave motion obtains when all the displacement currents and electron shifts arrive at their maximum and minimum deviations from normal simultaneously. If in a traveling wave there are spots in the wave form where energy undergoes conversion at maximum rate as compared to other portions of the wave, then it is reasonable to expect these spots to remain in one position with respect to an oscillating system undergoing standing wave motion for the reason that current and voltage are also standing in the system.

At low frequencies, the current distribution in everyday conductors is quite uniform, both with respect to depth under the skin of the conductor and with respect to its axial length, being practically the same at all cross-sections. As the frequency is increased to the point where the electric circuit components become comparable in dimensions to that wave length corresponding to the frequency, standing waves result due to reflection or partial reflection and then charges and currents sit and flow on the conductor surfaces. Potential energy is associated with the charges that sit and kinetic energy is associated with currents that flow. A measure of the potential state is expressed as a ratio of unit work to unit charge, that special ratio of joules to coulombs being designated as volts. In the case of the kinetic state, it is more convenient to introduce time into the comparison and the resultant ratio also expresses volts as the ratio between the time rate of doing work and the time rate of flow of charge, namely, watts per ampere. From this relationship the product of volts times amperes expresses power in watts.

This review leads us to another. In the case of low frequency systems, for instance 60 cycles, 75

the applied voltage may be the resultant of as many as three component voltages, inductive reactance, capacitive reactance and the voltage in phase with the current. As a consequence, the applied voltage is usually out of phase with the current. At any instant of time the instantaneous power may be calculated by taking the product of the instantaneous applied voltage and the instantaneous current. As a consequence, 10 also during one-half cycle with respect to time, there are established a positive envelope of energy and a negative envelope of energy, the negative being the smaller and representing the energy returned to the generator from the dominant reactive sink. As this slow frequency traveling wave of current progresses through the circuit at nearly the speed of light these positive and negative crests of the envelopes of energy speed with the wave and the positive differential 20 would of course produce uniform heating, say, in a resistance heating coil. The power expended in the resistor is then measured in watts by the relationship watts = I^2R , or E^2/R or $E \times I$ where E and I are given as effective values.

Contrast the above situation with the one associated with frequencies high enough to produce wave lengths comparable in size with the physical dimensions of the circuit boundaries with which they are associated. Also be reminded of the fact that due to the apparent reduced speed of wave propagation along a helix and across the gap of a condenser, it is possible, in the case of a standing wave condition, to study the results of the aforementioned power 30 crests with respect to space as well as time. As a consequence, any dielectric placed in the condenser gap will be heated throughout more or less non-uniformly provided a standing wave spans the gap. If the dielectric has high loss characteristics, such as high moisture content wood, then a high center heat obtains with resultant low amplitude of swing of the high frequency generator. On the other hand, if the dielectric is very low loss material, the amplitude of the generator will rise toward a maximum, the standing power peaks will separate and produce two relatively highly heated areas or sections each side of center between the condenser plates P , P' . The energy is decidedly not uniformly placed and the total energy expended 40 may be calculated from $E \times I \cos \theta$ where E and I are effective values. It leads to absurdity to use the formulae I^2R and E^2/R with respect to the standing state described because, using I^2R at the voltage antinode where I approaches zero, the product approaches zero, whereas, if E^2/R is used where E is maximum, the ratio yields a substantial amount.

The curves shown in Figures 6, 7, 8 and 9 are quite descriptive of this phenomena. If Figures 2, 3, 4 and 5 are folded upon themselves about the vertical axis P' , the result shows graphically the standing conditions of reactive voltage, applied voltage, current and positive and negative energy as they exist between the potential sinks of an oscillatory circuit in which the displacement currents and electron shifts are executing standing wave motion. The non-uniform placement of energy and the control of its placement as described herein assumes perfectly uniform physical and electrical properties of the material subjected to the electric and magnetic fields of force. It is also assumed that the components of the oscillating system are symmetrically disposed with respect to some

neutral axis and with respect to some neutral axis and with respect to adjacent objects and insulating supports.

The practice of electrode shaping, spacing, the use of auxiliary heat and of air gaps to control more or less the non-uniformity of energy placement has long been known. Variable physical and electrical properties in materials such as, for instance, knots, pitch pockets, variable densities, cracks, voids and differences in moisture contents in woods are disturbing but fortunately lie within practical safe limits. We combine known practices of field placement with the discovery of the natural non-uniform two spot concentrations of energy in the standing wave electric and magnetic fields of force to improve the control of heat placement in substances so processed.

As an example: To make a solid material such as a panel from resin impregnated sawdust, the electrodes must be spaced away from the finished surface and center section of the compressed sawdust by means of suitably thick, low loss cauls, as shown in Figure 8. The impregnated sawdust being high loss material tends to merge the two spots, thus resulting in a center cook with no cook at the face of the live electrodes. Thus the need for the cauls to position the cross-section of the sawdust at the center section where the energy is concentrated.

The procedures for showing the non-uniform heating patterns have been described. The exact methods of securing these non-uniform heating results are as follows:

1. For uniform heating of a package 6" wide, 10 inches long by $\frac{1}{2}$ " thick asbestos, bone dry (or very low moisture content) at 27 megacycles $\pm$, use 55" long inductance leads either side of center, condenser electrodes P, P', 16" long $\times$ 8" wide spaced $6\frac{1}{16}$ " apart with the dielectric therebetween, the short dimension (6") being across the electrodes.

2. For center heating, see Figure 9, of the package described in paragraph 1 above, all conditions are exactly the same except moisture content should be raised to a point sufficient to produce a large kinetic sink in the dielectric.

3. For heating the outside edges of the material and leaving the center cold to produce two spot heating as shown in Figure 7 and described above; at 27 megacycles $\pm$, use 86" long inductance leads either side of center, condenser plates $2\frac{1}{4}$ " $\times$ 16" spaced 10" apart with a dielectric of asbestos at room humidity of a size 6" $\times$ 10" $\times$ $\frac{1}{8}$ " with the long dimension placed between the electrodes. Thus, inductance has been increased and capacity reduced. This will produce extremely high temperatures in the edges of the dielectric nearest the electrodes and leave the material in the center relatively cool in comparison.

4. To produce the same two spot heating as described in paragraph 3 above, but draw the two spots closer together, the only change required from the conditions in paragraph 3 would be to increase the moisture content so as to create a greater kinetic sink of a higher loss. This brings the spots closer together and produces a condition where the center and the outside edges of the dielectric are relatively cool, and the two areas therebetween are hot.

To give a further illustration: if taking Figures 7, 8 and 9 at 27 megacycles, the two spot heating of Figure 7 would be produced by having an inductance longer and a capacity smaller

than the same components of either Figure 8 or 9. Also at the same 27 megacycle frequency, the relatively uniform distribution of heat obtained in Figure 8 across the dielectric "B," the inductance would be shorter than that in Figure 7 and longer than that of Figure 9; while the capacity would be greater than that of the capacity of Figure 7 and less than the capacity of Figure 9. Also at the same 27 megacycle frequency, the relatively high peaked center heating obtained in the dielectric as per Figure 9 is obtained with an inductance length less than that of either Figure 7 or 8, but a capacity between the electrodes P and P' greater than that between the corresponding elements of either Figure 7 or 8.

Assuming the same dielectric is heated, greater capacity can be had by increasing the area of the electrodes or reducing the space between the same sized ones; lesser capacity is the reverse; greater inductance increase can be had by increasing the physical length of the relative inductance component and a reduction can be had by reducing its length.

In all such adjustment to the field of force by arranging relations between inductance and capacity, the material being heated may or may not touch the electrodes of the radio circuit. This will depend on the capacity desired and other considerations, such as moisture content, dielectric constant, electrostatic strain in the R. F. field, and many other factors.

We claim:

1. The herein described process of heating dielectric material substantially uniformly by a radio frequency field of force which comprises: placing the material between the electrodes of a condenser in a radio circuit which includes inductance and capacitance, the total inductive and capacitative components of which limit the residence of radio frequency energy to but one single full standing wave comprising current and voltage curves; substantially the entire length of one-half of the wave residing in the condenser; regulating the phase angle between the current and voltage curves in the condenser so that they will overlap sufficiently for creating two power distribution curves whose crests will substantially coincide with the sides of the material and whose overlapping portions will create sufficient heat to equal substantially the heat generated at the two crests; whereby a more uniform internal heating of the material throughout its mass results.

2. The herein described process of heating a dielectric material by a radio frequency field of force to a higher degree in the center of the material than at its sides which comprises: placing the material between the electrodes of a condenser in a radio circuit which includes inductance and capacity, producing a radio frequency energy wave, regulating the phase angle between the current and voltage curves of said wave so that they will be in phase sufficiently for creating two power distribution curves whose crests will substantially merge and whose overlapping portions will create a combined heating effect greater than the heat of each separate crest; whereby a peaked heating effect is created in the interior of the material, between the said power crests.

3. The herein described process of heating dielectric material substantially uniformly by a radio frequency field of force which comprises: placing the material between the electrodes of

a condenser in a radio circuit which includes inductance and capacitance, the total inductive and capacitative components of which limit the residence of radio frequency energy to at least one single full standing wave having voltage and current curves; substantially the entire length of one-half of a single standing wave residing in the condenser; regulating the phase angle between the current and voltage curves in the condenser so that they will overlap sufficiently for creating two power distributing curves whose crests will lie within the material and whose overlapping portions will create sufficient heat to equal substantially the heat generated at the two crests; whereby a more uniform internal heating of the material throughout its mass results.

4. The herein described process of heating a dielectric material substantially uniformly by radio frequency field of force which comprises; placing the material between the electrodes of a condenser in a radio circuit which includes inductance and capacitance; producing a radio frequency energy wave having voltage and current curves; substantially the entire length of one-half of a single standing wave residing in the condenser; regulating the phase angle between the current and voltage curves of said wave in the condenser so that they will be in phase sufficiently for creating two power distribution curves whose crests will lie within the material and whose overlapping portion will create sufficient heat to equal substantially the heat generated at the two crests; whereby a more uniform internal heating of the material throughout its mass results.

5. The herein described process of heating a dielectric material by a radio frequency field of force to a higher degree at the opposite sides of the material than at the center which com-

5
10
15

prises: placing the material between a pair of cauls and arranging the electrodes of a condenser on the outer surfaces of the cauls; the condenser forming a part of a radio circuit which includes inductance and capacitance; producing a radio frequency energy wave having voltage and current curves; substantially the entire length of one-half of a single standing wave residing in the condenser; regulating the phase angle between the current and voltage curves of said wave in the condenser so that they will be in phase sufficiently for creating two power distribution curves whose crests will substantially coincide with the sides of the material and whose overlapping portions will create little heating effect within that portion of the material lying between the power curve crests; whereby the material will be heated to a greater extent at its opposite sides than at the center.
